UNITED STATES PATENT OFFICE.

EDWARD J. KELLY AND ELMER AINSLIE FORD, OF NEW YORK, N. Y.

DESIGN FOR A BOOK STONE OR STOP.

51,179.

Specification for Design.

Patented Aug. 21, 1917.

Application filed May 31, 1916. Serial No. 100,973. Term of patent 3½ years.

To all whom it may concern:

Be it known that we, EDWARD J. KELLY, a citizen of the United States, and ELMER AINSLIE FORD, a subject of the King of Great Britain and Ireland, both residing in the city, county, and State of New York, have invented a new, original, and ornamental Design for Book Stones of Stops, of which the following is a description, reference being had to the accompanying drawings, forming part thereof.

In the drawing Figure 1 is a front elevation and Fig. 2 a side elevation of a book stone showing our new design.

We claim—

The ornamental design for a book stone or stop as shown.

EDWARD J. KELLY.
E. AINSLIE FORD.
